MOP

Max L. Cass, Pasadena, Calif., assignor of four-tenths to Theodore Gutmann, Pasadena, Calif.

Application May 14, 1932. Serial No. 611,419

4 Claims. (Cl. 15—229.)

This invention relates to improvements in the class of mops and pertains particularly to an improved changeable head mop.

The primary object of the present invention is to provide a mop designed primarily for use in applying hot asphalt or hot tar, though not restricted to such use, in which the head may be easily removed for replacement by a new head.

Another object of the invention is to provide a mop having an improved head holder which is designed to prevent the strands of the mop head coming into contact with the holder and thus causing annoyance to the user, when the mop is used for applying hot tar or hot asphalt to roofs or other surfaces.

A further object of the invention is to provide a new and novel method of forming a mop.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

30 Figure 1 is a view in side elevation of the head end of a mop constructed in accordance with the present invention;

Figure 2 is a longitudinal sectional view taken substantially upon the line 2—2 of Figure 1.

35 Referring now more particularly to the drawing wherein like numerals of reference indicate corresponding parts throughout the several views, the numeral 1 indicates generally the holder of the mop embodying the present invention, while 40 the head of the mop is indicated generally by the numeral 2.

The head holder 1 comprises a sheet metal sleeve or cylinder of integral construction but designed to form three distinct portions which 45 are indicated by the numerals 3, 4 and 5. The portion 3 of the holder is of gradually increasing diameter from a point substantially midway between the ends of the holder body to one end, thus forming a flaring receiver or socket for the tapered end 6 of a handle 7.

50 The portion 4 which is intermediate the portions 3 and 5 is of constant diameter throughout and forms a sleeve for one end of the mop head 2 as will be hereinafter more fully described and the portion 5 is in the form of a

bell which constitutes an integral continuation of the intermediate portion 4, flaring outwardly therefrom as illustrated.

The mop head 2 is formed of twine known in the trade as mop yarn and comprises a plurality of strands of this yarn all cut to the same length and held in side by side relation. One end of the body of strands of which the head is made up is tightly compressed by clamping thereabout the metal jacket or band 8 and this jacket is pressed to a circumference which permits of it frictionally engaging in the intermediate sleeve portion 4 of the head holder 1. The flared or socket portion 3 of the holder is provided with suitable apertures 9 through which 60 a pin 10 may be driven to pass through the tapered tip or shank 6 of the handle and the sleeve portion 4 and the band or jacket 8 are provided respectively with the transversely aligned openings 11 and 12 which are brought 65 into alignment when the mop head clamping band is forced into the sleeve 4 so that the pin 13 may be forced therethrough and at the same time forced through the compressed strands of 70 the mop head. The strands will thus be more 75 tightly compressed in the jacket or band 8 and thus securely held against accidental displacement while the major portion of the head may be spread or frayed out as shown, to form a 80 suitable mop body.

85 While as previously stated the present mop is designed primarily for use in the application of hot tar or asphalt to roofs or other surfaces, it is, of course, to be understood that the device is not confined to such use but may be used in 90 any capacity where it is found suitable.

In the use of mops for the application of hot tar or asphalt the annoyance is frequently experienced of having the mop strands entangle about the forward end of the handle. This is 95 prevented in the present mop by the provision of the bell 5 at the forward end of the holder and in addition, this bell operates to prevent the tar or other liquid running back onto the holder and handle.

100 It will also be readily apparent from the foregoing that in the present mop after the strands of the head have worn down to the point where the head is no longer of use, it may be readily removed by extracting the pin 13 so that a new 105 head may be attached, it being contemplated to provide additional heads with the bands 8 attached for securing the strands at one end, so that the replacement of an old head may be accomplished without trouble or delay.

Having thus described the invention, what is claimed is:—

1. A mop, comprising a tubular shell, a handle having one end connected with an end of the shell, a mop head formed of strands of material, a sleeve of rigid material bound firmly about the ends of the strands at one end of the head, said sleeve being designed for insertion into the other end of the shell and having opposite apertures aligning with apertures in the shell, and a pin extending through the aligned apertures of the shell and sleeve, the said pin being forced through the mop strands and firmly wedging the same in and against the wall of the sleeve.
2. A mop, comprising a tubular shell, a handle having an end connected with an end of the shell, a mop head body formed of strands of material, a sleeve of rigid material encircling and binding the strands of said body together at one end of the body with said strands extending from the sleeve only at one end whereby the sleeve may be readily inserted into the

shell, and an elongated holding member for the sleeve inserted through an aperture in the wall of the shell and engaging the sleeve to secure it in the shell.

3. In a mop of the character described, an elongated shell, a handle secured at one end to an end of the shell, a mop head formed of a plurality of strands inserted at one end in compressed condition into the shell, and an elongated element extending transversely through the shell and through and in direct contact with the strands and further compressing the strands laterally against the wall of the shell.

4. The method of forming a mop head which consists in first compressing a body of mop strands together at one end, then inserting the said end of the strands in compressed condition into a hollow body, and then forcing an elongated member transversely through the hollow body and through the compressed body of strands therein to further compress the strands laterally against the wall of the hollow body.
